UNITED STATES PATENT OFFICE.

WALTER E. DEWEY, OF PHILADELPHIA, PENNSYLVANIA.

DESIGN FOR A VAGINAL SYRINGE.

SPECIFICATION forming part of Design No. 29,141, dated August 2, 1898.

Application filed April 5, 1897. Serial No. 630,860. Term of patent 3½ years.

To all whom it may concern:

Be it known that I, WALTER E. DEWEY, a citizen of the United States, residing at Philadelphia, in the county of Philadelphia and State of Pennsylvania, have invented and produced a new and original Design for Vaginal Syringes, of which the following is a specification, reference being had to the accompanying drawing, forming part hereof, in which is represented a perspective view of a syringe showing my design.

The leading feature of my design consists in a symmetrical figure or body of conoidal form, having its large end ovoidal in contour, but flat and provided with a central flat projection having two divergent nozzles, and its

small end rounded, with a nozzle-like end projecting therefrom.

a is the symmetrical body of conoidal form.

b is the flat end of ovoidal contour.

c is a round-ended nozzle that appears at the small end of the body *a*.

d and *e* are two divergent nozzles extended from a flat projection *f* in the center of the large flat end *b*, as shown.

What I claim is—

The design for a vaginal syringe substantially as shown and described.

WALTER E. DEWEY.

Witnesses;

A. L. KENNEDY,

A. B. STOUGHTON.
